UNITED STATES PATENT OFFICE.

LOUIS COURLANDER, OF CROYDON, ENGLAND.

CONSTRUCTION OF EYEGLASSES, SPECTACLES, AND THE LIKE.

1,079,932.

Specification of Letters Patent.

Patented Dec. 2, 1913.

Application filed August 5, 1911. Serial No. 642,436.

To all whom it may concern:

Be it known that I, LOUIS COURLANDER, a subject of the King of Great Britain, residing at No. 42 North End, Croydon, in the 5 county of Surrey, England, have invented new and useful Improvements in the Construction of Eyeglasses, Spectacles, and the like, of which the following is a specification.

10 This invention relates to improvements in means for supporting a lens in juxtaposition to the eye to serve for use in spectacles or "pince-nez." Hitherto the lens has been mounted in a removable manner in an inclosing frame the section of which and the periphery of the lens being such as to be adapted to make a secure connection each to the other when a screw or other fastening is employed to draw together and connect 15 the two otherwise unconnected ends of the inclosing frame. Alternatively to supporting the lens in a frame, as above described, the fittings for supporting the lens have been secured to the glass of the lens itself 20 by drilling a hole therein as in the so called frameless glasses.

By the present invention I derive the advantages of lightness and unobservability of the frameless glass and retain the strength 25 and durability of the frame-mounted lens.

According to the present invention I provide a band of very thin metal, which is of such length of circumference as to closely embrace the periphery of the lens, the band, 30 while having considerable strength to resist tension, being so thin and flexible as to conform to the shape of the profile of the lens. The contacting surfaces of the lens and embracing band are such as would be 35 generated by a straight line which, while always remaining perpendicular to the middle plane of the lens, traverses a closed curve. The lens is secured within the band by means of a cementing material. Such 40 a lens protected by being surrounded by a practically invisible rim will possess the unobservability feature of a frameless lens and at the same time will provide means whereby the nose-bridge and ear fittings for 45 supporting the lens can be secured thereto in a simple and strong manner. The methods of effecting the connection of those fittings to the embracing band may be greatly varied but their essential feature, according 50 to the present invention, is such as to permit any kind or proportion of bridge-piece or

other fitting to be secured to any kind or focal length of lens and thus enable an optician to completely satisfy the requirements of his customers with a minimum quantity 80 of stocked elements.

The accompanying drawing shows alternative methods of effecting the connection of the fittings to the permanently rimmed lens.

In this drawing the figures of which are, for the sake of clearness drawn on an enlarged scale:—Figure 1 is an end elevation of a lens drawn on a scale twice that of the other figures and showing the embracing band in section. Figs. 2-7 show one method of construction and assembly of the lens-band and the fittings to be secured thereto. Figs. 8-11 show methods of making the attachment to a plain band by gripping a portion of the band between two branches of a clamp, and Figs. 12 and 13 show another method of making the attachment by clipping a plain band.

In Fig. 1 the section of the band *a* is shown as having the shape of a very small segment of a comparatively large circle whereby the edges of the band are reduced to a minimum degree of thickness and visibility. The band is made from a rolled strip of metal which, according to one method of construction, is made endless by taking a suitable length and joining the two ends in any of the well known ways of forming a hoop by soldering or brazing them together with a butt or lap joint. Advantage may be taken of the opportunity of making the joint to braze or otherwise secure to the band a lug *a*¹, shown in Fig. 2, consisting of a short length of cylindrical tube, the 95 length being approximately equal to the width of the band. Alternatively, this lug may be independently brazed to the band away from the joint. The bridge-piece *b*, shown separately in Figs. 3 and 4 and in 100 dotted lines shown, in Fig. 2, assembled with one band-lug *a*¹, is so bent as to form the sides of a socket *b*¹ which surrounds the lug *a*¹ except the portion which is secured to the band. One end of the socket *b*¹ is closed 105 by a washer or nut *c* having a screw threaded aperture therein which washer or nut is advantageously brazed or otherwise secured to the socket *b*¹. The connection of the bridge-piece to the lug is completed by means of a 110 screw *d*, Fig. 5, and this latter is advantageously employed to carry the pivoted

2

nose-contacting element *e*. To insure a permanent connection of the band to the lens, the former, when it is a continuous hoop must have an internal periphery of such a 5 length as to exactly correspond to that of the external periphery of the lens. To facilitate the close embrace without requiring absolute precision of construction the ends of the band may be connected by an expansion joint as shown in Fig. 6 for example, in which the extremities of a U-shaped piece *a*² are brazed to the otherwise unconnected ends of the band, and in such manner provide a lug to fit the socket *b*¹. Alternatively, as in Fig. 7, the ends of the band are 10 bent to form hooks and these are inserted within a split ring *a*³. The said ring and extremities of the band may be permanently united by soldering or brazing or alternatively the screw *d* may be employed to 15 wedge the hooked extremities of the band into firm contact with the split ring when the parts are assembled together, with the split-ring inserted within the socket *b*¹. In Figs. 8 and 9, the band *a* which embraces the lens is a plain endless band without the lug *a*⁴. In this case, prior to cementing the lens within the embrace of the band, one or two very shallow recesses are formed 20 at the portion *f* of the periphery of the lens *f* the depth of the recess being just sufficient to receive the thickness of one branch of a clamp *g*, the other branch, in which is formed a screw-threaded aperture, passing 25 around the outside of the band, which latter is interposed between the two said branches of the clamp *g*. Prior to inserting the screws *h*, which draw together the two branches of the clamp, a portion of the 30 bridge-piece *b* is also inserted between the branches of the clamp *g*, being interposed between the band *a* and the outer branches of the clamp. The nose-contacting element *e* is swivelly mounted on the bridge-piece *b* 35 in the usual way. The clamp *g* may be permanently secured to the band by assembling it on the band prior to cementing the lens therein. In Figs. 10 and 11 a single clamp *g*¹ is 40 shown, the thin branch of which may be inserted within the band prior to the insertion of the lens and the cement and wedging action relied on to keep the clamp in place preparatory to securing by the screw *f*. In Figs. 12 and 13 an alternative method 45 of clipping the bridge fitting to the band *a*

is shown. In this case the bridge-piece *b* is formed with two ears *k* having an intervening space equal to the thickness of the lens at its periphery and the width of the 50 embracing band *a*. One of the ears has a plain orifice and the other a screw-threaded orifice for the reception of a screw *m*. A notch having been formed in the lens prior to being cemented within the band the 55 screw is inserted through the orifices in the ears and the notch in the lens and the two ears by being drawn together by means of the screw become tightly secured to the band. 70

When the invention is applied to the construction of spectacles, the ear-fittings are secured to the embracing lens-band in a manner similar to that described for the fastening of the bridge piece. 75

I claim:

1. For spectacles and the like eye-glasses, a lens and a rim-band composed of thin strip metal which closely embraces the periphery of the lens, the contacting surfaces of the 80 lens and band being cylindrical, such as would be generated by a straight line which traverses a closed curve, the lens and rim-band being retained in permanent connection by cement. 85

2. For spectacles and the like eye-glasses, a lens and a rim-band composed of thin strip metal which closely embraces the periphery of the lens, the contacting surfaces of the 90 lens and band being cylindrical, such as would be generated by a straight line which traverses a closed curve, the lens and rim-band being retained in permanent connection by cement, the rim-band being composed of a strip of metal whose edges have a 95 minimum thickness and visibility.

3. For spectacles and the like eye-glasses, a lens, a rim-band composed of thin strip metal which tightly embraces the periphery of the lens and an expansion joint for 100 slightly adjusting the length of the periphery of the band, the contacting surfaces of the lens and band being cylinders such as would be generated by a straight line which traverses a closed curve. 105

In testimony whereof I have signed my name to this specification in the presence of two subscribing witnesses.

LOUIS COURLANDER.
